UNITED STATES PATENT OFFICE.

FELIX ROQUE, OF NEW YORK, N. Y., ASSIGNOR TO THE BIGELOW CARPET COMPANY, OF BOSTON, MASSACHUSETTS.

DESIGN FOR CARPET.

SPECIFICATION forming part of Design No. 24,358, dated June 4, 1895.

Application filed March 22, 1895. Serial No. 542,858. Term of patent 3½ years.

To all whom it may concern:

Be it known that I, FELIX ROQUE, a citizen of the Republic of France, residing at New York, in the county and State of New York, have invented and produced a new and original Design for a Carpet, of which the following is a specification, reference being had to the accompanying drawing, making a part of the same, and is sufficient to enable others skilled in the art to make and use the same.

My invention consists of a border A, and body B, for a carpet.

The border A, consists of the representation at the top, of a floral scroll, and at the bottom, a narrow cross stripe, representing interlocking scrolls, and intermediate between the scrolls, a floral representation.

The body B, consists of a floral representation as shown.

What I claim as new, and desire to secure by Letters Patent, is—

1. In a design for a carpet, the border A, substantially as shown and described.
2. In a design for a carpet, the body B, substantially as shown and described.
3. The design for a carpet, consisting of the border A, and body B, substantially as shown and described.

FELIX ROQUE.
